UNITED STATES PATENT OFFICE.

FRANK H. LUMBARD, OF CHICAGO, ILLINOIS.

BRUSH.

No. 871,603.

Specification of Letters Patent.

Patented Nov. 19, 1907.

Application filed March 30, 1907. Serial No. 365,543.

To all whom it may concern:

Be it known that I, FRANK H. LUMBARD, citizen of the United States, residing at Chicago, in the county of Cook and State of Illinois, have invented certain new and useful Improvements in Brushes, of which the following is a specification.

This invention relates to improvements in brushes; and has for its object to provide a means for clamping the bristles in place and securing the brush and handle in their joint relation so as to simplify the operation of assembling the parts, and thereby saving valuable time and also increasing the durability of the completed article.

In the drawing, Figure 1 is a view in perspective of a ferrule looking at the upper side. Fig. 2 is a similar view looking at the under side. Fig. 3 is a transverse section of the ferrule through the body thereof. Fig. 4 is a sectional elevation showing the parts loosely assembled; and Fig. 5 is a similar view of the completed article.

A represents the handle, B the bristles and C a ferrule or cap used in the operation of firmly securing the respective parts in their assembled relation.

As this invention relates more especially to the flat type of brushes, that form is used in illustrating the improvement.

The ferrule C is an integral fabrication of thin sheet steel and for flat brushes the contour is of the oval elongated form shown. In the operation of manufacture the single piece of metal is struck up in the desired form, the center elongated part of the plate being forced upward or inward to provide a solid imperforate diaphragm 6 dividing the structure into the cupped out receptacles 40 forming the brush-socket 7 and the handle socket 8. The operation of forcing a portion of the ferrule blank inward or upward in providing the diaphragm feature, forms a double wall 9 below the same and a thickened bead edge 10 in the fold of the metal. This double-wall construction affords increased stiffness to the bottom edge of the ferrule inclosing the brush or bristle socket 7 and will more firmly clamp the butts of the bristles in place. The upper wall 11 inclosing the handle-socket 8 is of a single thickness which is sufficient for the purpose of securing the handle in place. The principal object of this design for a ferrule is to entirely dispense with the use of any adhesive composition or any fastening devices such as nails, screws,

wedges or wire in securing the different parts together. In the use of thin sheet steel a lighter ferrule can be made, than if cast or forged, which is another important advantage. The cost of production is also less.

In the operation of making the brush, the butt ends of the bristles are inserted in the socket 7 and bottom or level up on the diaphragm 6. A triangular shaped clamping wedge 12 is then loosely inserted dividing the butt ends of the bristles through the center, as shown in Figs. 4 and 5. It will be noted that the fixed position of the wedge brings one of the edges or corners 13 straight downward, the two opposite sloping sides 14 and 15 vanishing therein. The wedge is loosely slipped into place as it is not intended to exert an outward pressure, the bristles being secured by an inward pressure.

The contour and position of the clamping-wedge with reference to the binding bead edge of the ferrule is such, that when a pressure is exerted from the outside inward a kink or bend 16 will be formed in the bristles 80 by the pressure against the sloping or under-sides of the clamping wedge piece and will prevent any possibility of the bristles becoming loose or working out. After the center binding wedge is properly inserted the brush 85 is placed in a suitable machine and an inward all around die-pressure is applied to the binding bead edge 10 which bends the same inward and firmly clamps the bristles between the inner side of the double-wall of the 90 ferrule and the binding wedge, as shown in Fig. 5. By this means the bristles are compacted in place by frictional contact, no other or separate fastening being required. Fig. 4 shows the double wall and bead edge 95 in its normal constructive position for the bunching of the bristles.

The ferrule being capable of a change of form after the bristles are inserted, by setting the bead edge inward makes it possible 100 to more firmly secure the same in place than if the wall inclosing the brush socket was rigid.

The handle is provided with a continuous groove 17 and is secured in place by compressing the upper edge of the single wall 18 into said groove, as shown in Fig. 5.

Having thus described my invention, what I claim is—

1. A brush-ferrule, comprising in an integral structure, a bristle-socket, a handle-socket, and an imperforate division dia-

phragm, one of said sockets being inclosed by a double-wall having a bead edge, and the other socket inclosed by a wall-edge of a single thickness.

- 5 2. A brush-ferrule, comprising an integral structure, consisting of a brush-socket, a handle-socket, and a solid diaphragm on a line between said sockets, the brush-socket being inclosed by a double wall having a binding 15
10 bead edge adapted to be compressed inward in securing the bristles firmly in place.
3. A brush-ferrule of integral structure, comprising a brush-socket, a handle-socket,

and a division diaphragm, the brush-socket being inclosed by a double wall having a bead 15 edge and the handle-socket by a wall of a single thickness, the bristles, and a clamping wedge-piece inserted in the butt ends of said bristles.

In testimony whereof I have signed my 20 name to this specification in the presence of two subscribing witnesses.

FRANK H. LUMBARD.
